UNITED STATES PATENT OFFICE.

ALFRED WILKE, OF ALBANY, NEW YORK, ASSIGNOR OF ONE-FOURTH TO KARL H. WILKE, ONE-FOURTH TO F. RICHARD WILKE, AND ONE-FOURTH TO ROBERT F. T. WILKE, ALL OF ALBANY, NEW YORK.

ADJUSTABLE GEAR AND CYLINDER INTERLOCK.

Application filed February 28, 1927. Serial No. 171,702.

My invention relates to safety devices and particularly to safety devices which are adapted for attachment to washing machines, mixing machines, polishing machines, 5 and the like, which comprise a stationary cylinder enclosing revolving mechanism for operating upon articles placed within the cylinder. Such machines are generally provided with a sliding door or cover on the 10 side of the cylinder through which the machine is charged, and it is highly desirable that the interior mechanism should be rendered inoperative when this cover or door is open. It is equally desirable, that the 15 cover or door of such machines cannot be opened without stopping the machine, and that the machine cannot be placed in operation without closing the door.

Many machines of this character are 20 driven by belts running quite close to the end of the machine, and this is particularly true of most of the old style washing machines. Where this form of drive is employed, it is desirable that the interlocking 25 mechanism be operated without requiring the operator to swing his arm or body in the direction of the moving belt. It is also desirable that an interlocking mechanism of this character should be such that it is 30 readily adaptable to cylinders of different size.

With the attainment of these ends in view, the objects of my invention are to provide a gear and cylinder interlock which may be 35 operated by a direct push or pull away from or toward the front of the machine. Another object of my invention is to provide a device of this character which is adjustable to the extent that it may be attached to 40 cylinders of various machines without requiring a different set of parts for every type or size of machine. A further object of my invention is to provide means for accurately adjusting the gear interlock after 45 the device has been attached to the machine.

With these objects in view my invention includes the novel elements and the combinations and arrangements of elements described below and illustrated in the accompanying drawings in which—

Fig. 1 is a fragmentary end elevation of a machine of the character described illustrating the attachment of my interlock;

Fig. 2 is a plan view of Fig. 1;

Fig. 3 is a section of Fig. 1 in the plane 55 3—3 showing the driving gear in locked position and the cover unlocked;

Fig. 4 is a section similar to Fig. 3 showing the cover in locked position and the driving gear unlocked;

Fig. 5 is an inverted perspective view, 60 slightly enlarged, of a novel cam mechanism; and

Fig. 6 is a slightly enlarged perspective 65 view of the casting which supports the cam.

Referring to the drawings, 1 represents the stationary cylinder provided with the end or head, 2, and the sliding cover, 3. The mechanism within the cylinder, 1, may vary in character and is therefore not shown, 70 but it is to be understood that this mechanism is driven by the gear wheel, 4. Near each end of the cylinder a hoop, 5, is provided having a portion elevated above the surface of the cylinder as shown in Figs. 75 3 and 4 and which provides a groove or channel within which the sliding cover, 3, may be moved about to open the cylinder. The gear, 4, is provided with an annular 80 guard, 6, and a cover plate, 7. The annular guard has a cut out portion, 8, as shown in Figs. 1, 3 and 4 to permit the entrance of the locking lug or rack, 9. Attached to the head, 2, of the cylinder, just above the cut 85 out portion of the gear guard, is the rack 85 guide, 10, through which the rack is adapted to slide vertically.

The locking lug or rack, 9, may consist of a single casting provided with one or more teeth or projections adapted to interfit with 90 the teeth on gear wheel, 4. To provide for different sized cylinders and gears of different diameter the rack, 9, is provided in the upper side thereof with threaded openings 95 adapted to receive the bars, 11. These bars may be made of such length that they will fit the largest machines and the upper ends of the bars may be threaded down sufficiently to fit the smallest machines, as shown at 12. The rods, 11, pass through the yoke, 13, and are adjustably secured thereto by means of the nuts, 14, above and below the yoke. It has heretofore been the practice to cast the 100 rack and a carrier therefor, functioning similar to the rods, 11, in one piece which necessitates a special rack and carrier for every

different machine to which it is desired to attach the interlock. By providing an adjustable carrier for the rack it is obviously possible not only to fit every type of machine but to accurately adjust the interlock after installation.

Secured to the upper surface of the cylinder, near the edge thereof is the casting, 15, to which is pivoted the cover locking finger, 16. This finger is adapted to move in a vertical plane about its pivoted connection, as shown in Figs. 3 and 4. The portion of the finger over the cylinder is adapted to interfit with registering holes, 17 and 18, in the cover and cylinder, respectively, when the cover is in closed position. The outer end of the finger coacts with the yoke, 13, as shown, so that when the inner end of the finger is depressed to lock the cover, the outer end thereof is raised, carrying with it the yoke, 13, and disengaging the locking lug or rack, 9, and the gear, 4. To adjust the rise of the rack, the adjusting screw, 26, and the lock nut, 27, are provided. Slidably mounted upon the top of the casting, 15, is the operating cam, 19, provided with the hand grip, 20, and the inclined cam surfaces, 21 and 22. The operating cam, 19, is provided with a central slot, 23, adapted to receive a holding-down cap screw, 24, which is threaded into the casting, 15. To prevent the operating cam from being jarred either from the locked or unlocked position, I provide the helical spring, 25, which is compressed between the head of the cap screw, 25, and the top surface of the cam.

When the parts are in the relative position shown in Figs. 1, 2 and 3 the cover is unlocked and the gear is locked. When the operating cam is pushed in the direction of the arrow shown in Fig. 1, to the position, 19', the cam surfaces, 21 and 22, coacting with the finger, 16, move it to the position shown in Fig. 4 whereby the cover is locked and the gear is unlocked.

I am aware that interlocks of this general character have been used by others and it is to be understood that I do not claim, as my invention the broad combination herein disclosed.

My invention being more particularly directed toward providing the adjustable features described in an interlock of this character, and in the novel elements and combinations whereby a direct "push and pull" method of operation is attained.

What I claim is—

1. In a gear and cylinder interlock of the character described, the combination with means for actuating the interlock, of a lug adapted to lock the gear, a carrier for said lug coacting with the actuating mechanism, and means for varying the distance between the actuating mechanism and the lug. 60
2. In a gear and cylinder interlock of the character described, the combination with means for actuating the gear lock, of a lug adapted to lock the gear, a yoke adapted to coact with the actuating mechanism, and connecting means for the yoke and lug adjustable to vary the distance between said connected elements. 65
3. In a device of the character described, a gear lock comprising a block provided with a projection adapted to interfit the teeth of said gear, and a carrier for said block comprising a threaded rod adapted to effect a connection of adjustable length between the block and the actuating mechanism therefor. 70
4. In a device of the character described, a gear lock comprising a block provided with a projection adapted to interfit the teeth of said gear, a yoke adapted to coact with an actuator for said lock and a connecting means for said block and yoke comprising threaded rods provided with nuts either side of said yoke whereby the distance between the yoke and block may be varied. 75
5. In a gear and cylinder interlock, the combination with a supporting element, of a finger lever pivoted thereto adapted to actuate the gear lock, and means for positively operating the finger lever comprising oppositely inclined cams having a straight line movement and slidably coacting with said finger lever at either side of the pivotal connection. 80
6. In a gear and cylinder interlock of the character described, an operating element comprising a flat metal block provided with parallel, depending portions at either side thereof forming cam surfaces oppositely inclined to the plane of the block. 100
7. A gear and cylinder interlock of the character described comprising the combination with means for actuating the interlock, of a lug adapted to lock the gear, a carrier for said lug coacting with the actuating mechanism, a guide for the lug and carrier, and means for varying the distance between the actuating mechanism and the lug. 105

ALFRED WILKE. 110
